UNITED STATES PATENT OFFICE

172,549

BIB

Harold A. Owen and Phyllis A. Turner, Dover,
Del., assignors to International Latex Corporation, Dover, Del., a corporation of Delaware

Application December 16, 1953, Serial No. 28,110

Term of patent 14 years

(Cl. D3—26)

To all whom it may concern:

Be it known that we, Harold A. Owen and Phyllis A. Turner, citizens of the United States and residents of Dover, in the county of Kent and State of Delaware, have invented a new, original, and ornamental Design for a Bib, of which the following is a specification, reference being had to the accompanying drawing, forming part thereof, wherein:

We claim:

The ornamental design for a bib, as shown.
